ATTORNEYS.

UNITED STATES PATENT OFFICE.

WILLIAM HARRY JOSLIN, OF PROVIDENCE, RHODE ISLAND, ASSIGNOR TO SHOE LACE COMPANY, LTD., OF PROVIDENCE, RHODE ISLAND, A CORPORATION OF RHODE ISLAND.

BOX.

Application filed June 16, 1926. Serial No. 116,366.

This invention relates to an improved construction of box more particularly adapted for use in carrying and displaying merchandise, such for instance as a plurality of pairs of lacings in banded bundles set side by side, the box being provided with a body portion having an insert member therein forming a lining for the sides and end walls thereof, some of said walls having inturned, 10 integral retaining edge flanges and one of said walls having a flap or lid to be folded down over the contents of the box.

With these and other objects in view, the invention consists of certain novel features 15 of construction, as will be more fully described, and particularly pointed out in the appended claims.

In the accompanying drawings:

Figure 1 is a perspective view of my 20 improved box with its telescoping inclosing cover removed and the lid raised showing the lining member therein.

Figure 2 is a side elevation showing the strip of cardboard with one of its side wall 25 portions and both of the end walls as being provided with flanged portions and one of its side wall portions as having a flap or lid portion.

Figure 3 shows the insert or lining as 30 folded to form two end walls and two side walls, the end walls and one of the side walls as being provided with the lid or flap member.

Figure 4 shows the body of the box into 35 which this lining or insert fits.

Figure 5 shows the lining or insert as having been positioned into the body of the box, the box being filled with a plurality 40 of bundles of lacings, a portion of the edge flanges being broken away to show the rounded edges of the bundles which the flanges are to cover.

Figure 6 shows the box body with the flap or lid of the insert as turned down thereover to hide the contents of the box.

Figure 7 shows the telescoping cover removed from the box.

Figure 8 is a longitudinal section of my 50 improved box showing the upper edge in-turned flanges and the lid or flap of the insert overlying these edges and the telescoping cover inclosing the whole.

Figure 9 is a transverse sectional view of the part shown in Figure 8 also illustrating

in dotted lines a bundle of lacings inclosed 55 within the box.

It is found in the practical use of boxes more particularly those employed for carrying such bundled goods as lacings and the like, of advantage to provide an edge flange 60 about three sides of the body of the box under which the edge of the lacing bundles are caused to be inserted leaving one side free to permit easy positioning of the bundles into the box, and to provide a box 65 of this character, it is found of advantage to form the body of the box of relatively heavy material and then to provide a lining or insert of a lighter material of better quality having a surface well adapted to be 70 lithographed or printed upon, and to cut this insert from a strip of card board with all of its parts integral whereby the end walls and one of the side walls are provided 75 with inturned lips or flanges and the other side wall being provided with a lid or flap which is of a size and shape to be folded over to hide the contents of the box. The inturned flanges serving to assist in retaining the bundles of the lacings in position in 80 the body of the box and also serving to provide an attractive finish about the edge of the box to cover the spaces between the ends of the bundles of lacings and the sides of the box and so present a more finished and 85 attractive appearance to the package. The flap or lid providing an extended surface for carrying advertising matter; and the following is a detailed description of the present embodiment of my invention and showing 90 one construction of box by which these advantageous results may be accomplished:

With reference to the drawings, 10 designates the body of the box which is usually made of cardboard to serve as a relatively 95 stiff carrier for the contents thereof. To complete this box in the desired manner, I provided a lining of a thinner and better quality than the material of the body of the box, and one which is more flexible and pliable and which is provided with a surface better adapted to receive lithographed or printed matter thereon, and to this end, I have formed a lining or insert 11 which is preferably formed of a strip of relatively thin cardboard as best illustrated in Figure 100 2. The strip after having been cut to the desired length and shape is folded into a 105

frame-like shape as best illustrated in Figure 3 having end walls 12 and side walls 13, the end walls being provided with integral, inturned flanges 14 and one of the side walls 5 being provided with an integral, inturned flange 15, the adjacent edges of which may be secured together if desired by any suitable means such as gumming, clipping, or the like, the opposite side wall of the lining 10 being provided with an integral lid or flap 17 of a size to fold down and cover the flanges 14 and 15, as well as the contents of the box. This lining or insert is then positioned in the box body to fit about its side 15 and end walls, thus leaving one side without a flange to permit the ready positioning of the bundles of lacings 18 into the box to be moved laterally beneath the inturned flanges which serve to firmly secure these bundles 20 in position.

It will be noted that bundles of lacings of this character are somewhat rounded on their edges, and, therefore, can not fit closely into the box to completely fill the same about 25 its upper edge. Therefore these inturned flanges 14 and 15 serve to cover these rounded edges and give to the package a more finished and attractive appearance in addition to more firmly securing the bundles in position 30 in the body of the box.

The flap or lid 17 may be printed or carry any desired advertising matter on both its inner and outer surfaces and therefore one of the surfaces will be exposed when the lid 35 is open and the other when the lid is closed.

In shipping the packages the lid 17 is closed down over the contents of the box and a telescoping cover 19 is provided to slip down over the body to inclose the whole, 40 this cover being of a relatively heavy quality to protect the goods and the box body during transportation.

My improved box with the insert or lining 45 therein is very simple, practical and inexpensive in construction and by the use of the

inturned flanges thereon the goods are firmly retained in the box, the flanges also serving to cover the unoccupied portions of the package when the goods are packed therein, these flanges also providing additional surface 50 for carrying advertising matter if desired and to impart to the package a finished and attractive appearance when the lid is raised to display the contents of the box.

The foregoing description is directed 55 solely towards the construction illustrated, but I desire it to be understood that I reserve the privilege of resorting to all the mechanical changes to which the device is susceptible, the invention being defined and limited only by the terms of the appended claims.

I claim:

1. A box comprising a body member having a bottom and side and end walls, which 60 walls are connected together, and insert member fitted to line said body member comprising an integral continuous strip of four connected portions adapted to be folded to form side and end walls, each end wall and 65 one side wall of the insert member having inturned upper edge flanges, and the other side wall of the insert member having a flap to swing down and cover the contents of the 70 box.

2. A box comprising a body member having a bottom and side and end walls, which 75 walls are connected together, an insert member fitted to line said body member comprising an integral continuous strip of four 80 connected portions adapted to be folded to form side and end walls, each end wall and one side wall of the insert member having inturned upper edge flanges, and the other 85 side wall of the insert member having a flap to swing down and cover the contents of the box, and a telescoping cover member to fit over the body member and contents.

In testimony whereof I affix my signature.

WILLIAM HARRY JOSLIN.
